UNITED STATES PATENT OFFICE.

HARVEY J. LOUNSBURY, OF GLEN ELLYN, ILLINOIS, ASSIGNOR TO W. H. MINER, INC., OF CHICAGO, ILLINOIS, A CORPORATION OF DELAWARE.

RELEASE SPRING ARRANGEMENT FOR FOUNDATION BRAKE RIGGING.

Application filed January 16, 1926. Serial No. 81,623.

This invention relates to foundation brake riggings.

The purpose of the present invention is to provide means for quickly releasing the 5 brake rigging of a railway car after application of the brakes either by the usual air brake mechanism or hand-brake mechanism, and quickly restore the rigging to fully released position so as to prevent dragging 10 of the brake shoes against the wheels which occurs in actual practice when the rigging is permitted to slacken gradually of its own volition.

A more specific object of the invention is 15 to associate resilient means with the ordinary air and hand brake equipment in such manner that the resilient means is compressed during application of the brakes either by air, or by hand, and operates to 20 immediately release the hand brake rigging by exercising a pull thereon to completely unwind the brake staff, and further to restore the push rod of the air brake to fully 25 released position, whether the air and hand brake equipment is operated simultaneously or independently to apply the brakes.

Other and further objects of the invention will more fully and clearly appear from the description and claims hereinafter following.

In the drawing, Fig. 1 is a fragmentary top plan view of the under frame of a railway car, showing an ordinary type of air brake, brake lever, and a portion of the hand 35 brake rigging, and illustrating my invention in connection therewith. And Fig. 2 is a side elevation of a fragment of the under frame of a railway car, illustrating the air brake cylinder in partial section, together 40 with a portion of the winding staff of the hand brake, and illustrating my invention in connection therewith.

As illustrated in the drawings, 10 indicates a center sill or other beam member 45 forming part of the under frame of a railway car, upon which may be mounted an air brake of a well known type, indicated as a whole by the reference numeral 11. The air brake includes the usual reservoir 12 50 to which is connected the air cylinder 13 having the usual piston head 14, and hollow guide rod 15 slidably mounted therein, a helical spring 16 being disposed about the rod 15 and bearing against the piston head 55 14 and the forward wall 17 of the cylinder.

A push rod 18 is slidably mounted within the rod 15, said rod 18 having an inner enlarged portion 19 adapted to abut the wall 20 forming part of the piston head 14. Said push rod when the same is in its innermost position extends outwardly beyond the end of the guide rod 15, and terminates in a forked portion 21, between the furcations of which is disposed one end 22 of the brake lever 23, which extends horizontally and transversely beneath the car underframe in the usual manner. The brake lever 23 is provided with the usual cylinder rod 24 pivotally connected thereto, and with pull rod 25, forming part of the brake rigging. 70

Attached to the outer end of the push rod 18 is the usual hand brake rod 26, said rod being provided with a forked portion 27, the furcations of which fit over the outer sides of the forked portion 21 of the push rod, a 75 connecting pin 28 extending through the forked portions 27, 21, and the end 22 of the brake lever 23, thus securing the parts together for pivotal movement. The hand brake rod 26 may be connected to the brake staff 29 by rod 30, and winding chain 31 is looped over a rotatable pulley 32 at the end of the rod 30, the ends of the chain 31 being secured to the brake staff 29 and brake shaft step. 80

The construction thus far described is of well known form, and no claim is made herein to the same, except in combination with the releasing mechanism hereinafter described. 85

The brake rigging above described, while reasonably efficient, is open to the very serious objection that after an application either by air or by hand, the rigging is not released by any positive means, but is permitted to gradually release through vibration and jar-ring of the parts. For instance, when the chain 31 is wound upon the brake staff 29, to apply the brake, and the staff is subsequently released, the release depends upon the pull of the brake rigging upon the winding chain, which pull progressively grows weaker and therefore slower, as the mechanism approaches fully released position which frequently is never reached, resulting in dragging of the brake shoes on the wheels, which brings about excessive wear, and increases the tractive effort necessary to move the car. This condition is exactly the same when the brakes are applied by air, since 100 105 110 115 120 125 130 135 140 145 150 155 160 165 170 175 180 185 190 195 200 205 210 215 220 225 230 235 240 245 250 255 260 265 270 275 280 285 290 295 300 305 310 315 320 325 330 335 340 345 350 355 360 365 370 375 380 385 390 395 400 405 410 415 420 425 430 435 440 445 450 455 460 465 470 475 480 485 490 495 500 505 510 515 520 525 530 535 540 545 550 555 560 565 570 575 580 585 590 595 600 605 610 615 620 625 630 635 640 645 650 655 660 665 670 675 680 685 690 695 700 705 710 715 720 725 730 735 740 745 750 755 760 765 770 775 780 785 790 795 800 805 810 815 820 825 830 835 840 845 850 855 860 865 870 875 880 885 890 895 900 905 910 915 920 925 930 935 940

there are no means for returning the push rod to its innermost position with reference to the piston head. The combined result of the factors above mentioned causes an unsatisfactory release of the brake rigging, and as above stated it is my purpose to effect a full and rapid release of the rigging by a simple means, which operates to release the rigging whether operated by air or by hand, 10 simultaneously, or independently.

The means by which the desired release of the brake rigging is accomplished, as shown in the drawings, consists in providing a bracket 40, the legs 41 of which are riveted to the center sill 10 as indicated at 42, preferably in proximity to the hand brake rod 26, the outer end 43 of the bracket having an aperture for the slidable reception of the hand brake rod 26, the outer portion 43 15 providing a stationary abutment. Interposed between the stationary abutment provided by the end 43 of the bracket, and the abutment 44 formed by the forked portion 27 of the brake rod 26, is a helical spring 45, said spring bearing against the stationary abutment formed by the end of the bracket 43 and the abutment 44 provided by the forked end 27 of the brake rod 26, said spring being of suitable strength so as to 20 urge the end 27 of the brake rod, the end 22 of the lever 23, and the push rod 18 of the air brake mechanism in a direction to effect full released position of the brake rigging.

In operation, upon admission of air to the 35 brake cylinder 13, outward movement of the piston head 14 of course effects outward movement of the push rod 18, which operates the brake lever 23 to set the brakes, and at the same time compresses the spring 40 45 against the abutment 43 formed by the bracket 40, and when the air is released from the cylinder 14, said spring urges push rod toward its innermost position carrying the brake lever 23 therewith, with a consequent full release of the brake rigging. Likewise when the hand brake is applied, 50 movement of the brake rod when acted upon by the chain 31 being wound on the brake staff, will compress the spring 45, which when the brake staff 29 is released, will urge the brake rod 26 and brake line 23 toward fully released position, assuring complete 55 unwinding of the chain from the brake staff, and the withdrawal of the brake shoes from engagement with the wheels. Compression of the spring 45 also results upon the combined application of the brakes by the hand brake mechanism and air brake mechanism, and when said mechanisms are 60 released, the spring 45 will operate to return

the hand brake mechanism and air brake mechanism to the initial completely released position of the brake rigging.

While I have herein shown and described what I now consider the preferred manner of carrying out my invention, the same is merely illustrative, and I contemplate all changes and modifications that come within the scope of the claims appended hereto.

What I claim is:

1. In a brake mechanism of the character described, the combination with brake rigging including a winding element and a transmitting member; a fixed bracket secured to the car structure, an operative connection between said transmitting member and said winding element, said connection having a portion adapted to be wound on said winding member to operate said transmitting member to tighten said brake rigging; said operative connection extending through said bracket, and resilient means comprising a coiled spring disposed about a portion of said connection and having one end bearing on said transmitting member and the opposite end on said bracket and adapted to be compressed when said connection is moved by said winding element to tighten said rigging, said resilient means operating to exert a pull upon said connection to fully unwind the winding element when the same is released to entirely slacken said brake rigging.

2. In a mechanism of the character described, the combination with a railway car; a brake rigging for said car including a brake lever; an air brake mechanism mounted upon the car structure and including an air cylinder and piston; a hand brake having a connection with said brake lever at one end thereof; a push rod associated with said air brake mechanism and connected to said lever at said end, said push rod being free to move without operation of said piston when said hand brake mechanism is operated; and resilient means in the form of a coiled spring interposed between a fixed portion of the car structure and said brake lever and disposed about said connection, whereby the same is compressed by movement of said brake lever in a direction to apply the brakes, said resilient means operating to move said lever in the reverse direction when the brake applying means are free.

In witness that I claim the foregoing I have hereunto subscribed my name this 13th day of January 1926.

HARVEY J. LOUNSBURY.
